<https://coldrivermining.com/product/castle-slue/> (Year: 2024).*Primary Examiner — Patricia A Palasik(74) *Attorney, Agent, or Firm* — CARRITHERS LAW OFFICE, PLLC; David W. Carrithers(57) **CLAIM**

The ornamental design for a twin tower castle sluice as shown and described.

DESCRIPTION

FIG. 1 is a perspective view of a twin tower castle sluice showing my new design;

FIG. 2 is a front view thereof;

FIG. 3 is a rear view thereof;

FIG. 4 is a top view thereof;

FIG. 5 is a bottom view thereof;

FIG. 6 is a right end view thereof; and,

FIG. 7 is a left end view thereof.

The broken lines showing the tray in FIG. 3 and the sluice and tray in FIG. 4 are for the purpose of illustrating environmental subject matter and form no part of the claimed design.
